(57) **CLAIM**

The ornamental design for an antenna, as shown and described.

DESCRIPTION

FIG. 1 is a front elevational view of an antenna showing my new design;

FIG. 2 is a rear elevational view thereof;

FIG. 3 is a right side elevational view thereof;

FIG. 4 is a left side elevational view thereof;

FIG. 5 is a top plan view thereof;

FIG. 6 is a bottom plan view thereof;

FIG. 7 is a front, top perspective view thereof;

FIG. 8 is another front, top perspective view thereof;

FIG. 9 is a bottom, rear perspective view thereof;

FIG. 10 is a front elevational view of a second embodiment of an antenna showing my new design;

FIG. 11 is a rear elevational view thereof;

FIG. 12 is a right side elevational view thereof;

FIG. 13 is a left side elevational view thereof;

FIG. 14 is a top plan view thereof;

FIG. 15 is a bottom plan view thereof;

FIG. 16 is a front, top perspective view thereof;

FIG. 17 is another front, top perspective view thereof; and,

FIG. 18 is a bottom, rear perspective view thereof.
